UNITED STATES PATENT OFFICE.

WALTER KIESER AND GUSTAV PAGEL, OF CHARLOTTENBURG, GERMANY, ASSIGNEES
TO GENERAL ELECTRIC COMPANY, A CORPORATION OF NEW YORK.

PUMP.

1,215,282.

Specification of Letters Patent.

Patented Feb. 6, 1917.

Application filed October 20, 1915. Serial No. 56,969.

To all whom it may concern:

Be it known that we, WALTER KIESER, a citizen of the Swiss Republic, and GUSTAV PAGEL, a subject of the King of Prussia, both residing at Charlottenburg, Germany, have invented certain new and useful Improvements in Pumps, of which the following is a specification.

The present invention relates to centrifugal pumps of the type having an impeller which receives the liquid being pumped at the side and discharges it at the periphery. With such pumps when the supply of liquid being pumped is small and below the capacity of the pump more or less, air is sucked in and discharged with the fluid, since the liquid does not at such times wholly cover the admission opening or eye of the impeller. Although this is unobjectionable in various installations, yet in many cases it is highly objectionable, as, for example, in pumps used for pumping the water of condensation from condensers, which water is used as feed water, as the air therein may cause corrosion of the walls of the boilers.

The object of the present invention is to provide an improved arrangement or structure in a pump of this type which will prevent at all times air being sucked into the impeller and discharged along with the liquid being pumped.

For a consideration of what we believe to be novel and our invention attention is directed to the accompanying specification and the claims appended thereto.

In the drawing wherein we have illustrated one form which our invention may take, Figure 1 is a sectional view through a pump, and Fig. 2 is a section taken at right angles to Fig. 1.

Referring to the drawing, 5 indicates the suction chamber of the pump casing having the admission opening 6, and 7 indicates the discharge scroll which terminates in the discharge pipe 8. 9 indicates the pump shaft which extends into the casing through a suitable packing 10 and carries on its end the impeller 11 provided with vanes 12. 50 This impeller may be of any usual or desired structure. It receives the liquid to be pumped at the side and discharges it at

the periphery, as is well understood. The structure so far described is that of an ordinary type of pump. When such a pump 55 is in operation it will be clear that, when the whole admission area of the impeller is not covered with liquid to be pumped, air will be sucked into the impeller. One way to prevent this, in accordance with our invention, is that illustrated in the drawing in which a wall 13 is provided in the suction chamber of the pump which defines passages 14 and 15, and an admission opening 16 to the impeller, which opening is located 60 at the bottom of the impeller. This wall 13 forms in effect a partition in the suction chamber and projects down so far that air can not enter the admission opening 16 even at the lowest level of the water. In other 70 words, it forms a trap or liquid seal for the inlet side of the impeller. Viewed from a different aspect it may be considered that the chamber formed by the partition member 13 in front of the eye of the impeller is 75 the suction chamber of the pump and that passages 14 and 15 are conduits for directing the liquid through the opening 16 to the impeller.

In operation the passages 14 and 15 carry 80 the liquid to be pumped down around the impeller and it enters the space in front of the eye of the impeller through opening 16. Here it is taken by the impeller and discharged into the scroll 7 and thence to outlet 85 8.

The arrangement also has the advantage that it is more economical in the consumption of power since the required power will always correspond to the effective output of 90 the pump for the time being. This is due to the fact that the pump is never called upon to pump anything except the liquid intended.

In accordance with the provisions of the 95 patent statutes, we have described the principle of operation of our invention, together with the apparatus which we now consider to represent the best embodiment thereof; but we desire to have it understood that the 100 apparatus shown is only illustrative, and that the invention can be carried out by other means.

What we claim as new and desire to se-

cure by Letters Patent of the United States, is:—

1. In a liquid pump, the suction opening of which is at times only partially supplied with liquid, the combination of a casing, an impeller in the casing, a wall surrounding the eye of the impeller and forming a suction chamber directly in front of it, said wall having an opening at its lower portion, and means forming a conduit for supplying fluid to said opening, said conduit extending from a point above the opening down to it whereby the fluid will be supplied to it by gravity and a trap formed to prevent the admission of gases to the impeller.
2. The combination with a centrifugal pump having a suction chamber, of a partition member in the suction chamber which surrounds the eye of the impeller and de-

fines an opening at the lowest point thereof for the admission of the liquid to be pumped to the impeller.

3. The combination of a casing having an inlet, an impeller in the casing, a discharge scroll surrounding it, and a partition member in the casing which surrounds the eye of the impeller and has an opening at its lowest point for admitting liquid to the impeller, said partition member defining a passage for conveying liquid from the inlet to said opening.

In witness whereof, we have hereunto set our hands this 23 day of September, 1915.

WALTER KIESER.
GUSTAV PAGEL.
